DESIGN FOR A CEILING LIGHTING FIXTURE

Gordon B. Hurlbut, Watertown, Conn., assignor to The Plume & Atwood Manufacturing Company, Waterbury, Conn., a corporation of Connecticut

Application June 12, 1936, Serial No. 63,255

Term of patent 3½ years

To all whom it may concern:

Be it known that I, Gordon B. Hurlbut, a citizen of the United States and residing at Watertown, in the county of Litchfield and State of Connecticut, have invented a new, original, and ornamental Design for Ceiling Lighting Fixtures, of which the following is a specification, reference being had to the accompanying drawing, forming part thereof.

The figure is a view in elevation of a ceiling lighting fixture showing my new design.

The dominating characteristics of my design consist in the harmonious relationship between the flared lower lamp receptacle and the flared cylindrical neck above it, with the suspending connection between the canopy and the depending pipe.

I claim:

The ornamental design for a ceiling lighting fixture as shown and described.

GORDON B. HURLBUT.
